UNITED STATES PATENT OFFICE.

WILLIAM C. WARING, OF YONKERS, NEW YORK.

FULLING-MILL.

SPECIFICATION forming part of Letters Patent No. 248,537, dated October 18, 1881.

Application filed September 1, 1881. (Model.)

To all whom it may concern:

Be it known that I, WILLIAM C. WARING, of Yonkers, in the county of Westchester and State of New York, have invented certain new and useful Improvements in Fulling-Mills, of which the following is a specification, reference being had to the accompanying drawings, forming part of this specification, in which similar letters of reference indicate corresponding parts in all the figures.

Figure 1 is a side elevation of my improvement, the side of the fulling-box being removed. Fig. 2 is a plan view of the same, partly in horizontal section and part being broken away. Figs. 3 and 4 are side elevations of the crank-wheels.

The object of this invention is to promote convenience and economize expense in operating fulling-mills.

20 The invention consists in the combination, with the shaft that operates the hinged lining-plate and the cam-roller that operates the beater, of the crank-wheels and the connecting-rod, whereby the said hinged lining-plate will be operated automatically from the said cam-roller, as will be hereinafter fully described.

A represents the fulling-box, the rear part of the interior of which is curved upon the arc of a circle having for its center the axis of the beater B. The forward part of the box A is made upon a smaller curve and its upper part is extended inward to prevent the liquid contents of the box from spattering and the material being operated upon from being forced out by the said beater. The rear part of the box A is lined with a metal plate, C, to prevent the bottom from being worn by the beater. The forward part of the box A is lined with a metal plate, D, to prevent it from being worn by the material being operated upon. The adjacent edges of the plates C D are hinged to each other to allow the upper part of the forward plate, D, to be moved inward to turn the material. The hinge E of the plates C D enters a recess in the bottom of the box A.

45 The beater B is curved upon the arc of a circle, and has its forward end rabbeted to form a series of shoulders. The beater B is attached to two bars, F, the outer ends of which are secured to a shaft or rod, G, which works in

bearings in the upper ends of the arms or brackets H, formed upon or attached to the forward end of the box A. The inner ends of the bars F project, and to and between them is hinged the lower end of the board or plate I, which passes up between two rollers, J K. The roller J revolves in bearings in the upper ends of the arms or brackets L, attached to or formed upon the rear end of the box A.

55 To one journal of the roller J is attached a pulley, M, to receive the driving-belt. To the other journal of the roller J is attached a cone-pulley, N, around which passes a belt, O. The belt O also passes around a cone-pulley, P, attached to a journal of the cam-roller, Q, the journals of which revolve in bearings in the lower parts of the brackets L.

To a journal of the roller J is attached a gear-wheel, R, the teeth of which mesh into the teeth of the gear-wheel S, attached to a journal 70 of the roller K, so that the said roller K will be revolved from and by the roller J. The journals of the roller K revolve in bearings in the upper ends of the bars T, which are fulcrumed to lugs formed upon the brackets L. 75 The lower ends of the bars T project nearly to the side of the cam-roller Q.

To the middle parts of the bars T are hinged the upper ends of the bars U. The lower parts of the bars T U are drawn toward each other 80 by rubber or spiral springs, or other suitable springs, V, attached to them, and are kept from being drawn too close together by stop-blocks W, interposed between them and attached to one or the other of the said bars.

85 To the lower ends of the bars U is pivoted a small roller, X, which bears against the side of the cam-roller Q. With this construction, when the roller X rests against the larger part of the cam-roller Q, the roller K will be forced 90 toward the roller J, so that the board I will be clamped between the said rollers K J with so much force that it will be carried up by and between the rollers K J, raising the beater B. As the roller X passes to the smaller part of 95 the cam-roller Q the pressure of the roller K toward the roller J will be relaxed so much that the board I will be released and the beater B allowed to fall against the material in the fulling-box A.

To the upper edge of the forward lining-plate, D, are hinged the ends of two connecting-rods, Y, the other ends of which are hinged to the outer ends of two arms, Z, formed upon 5 or attached to the shaft a. The shaft a works in bearings attached to the upper forward corners of the fulling-box A or in the brackets H. With this construction, by turning the shaft a, the upper part of the lining-plate D will be 10 swung inward so as to dislodge the material from the place into which it has been driven by the beater B and turn the said material over, so that it will be struck by the said beater B in a new place. This has heretofore 15 been done by means of a crank attached to the end of the shaft a, and necessitated the employment of an attendant for that purpose.

In my improvement I replace the crank by a crank-wheel, b, to the crank-pin of which 20 I pivot the end of a connecting-rod, c, the other end of which is pivoted to the crank-pin of the crank-wheel d, attached to the journal of the cam roller Q, so that the lining-plate D will be operated automatically from the said 25 cam-roller Q to turn the material. Several holes are formed in the crank-wheels b d to receive the crank-pins, so that the throw of the lining-plate D can be regulated, as required. The crank-pins of the crank-wheels b d should 30 be so arranged that the revolution of the crank-wheel d will only rock the crank-wheel b.

If desired, the connecting-rod c can be formed of two rods having screw-threads upon their ends to receive the nuts by which they are secured to the ends of cross-heads that are pivoted at their centers to the crank-pins of the 35 crank-wheels b d.

The advantage of this construction is that it allows the connecting-rod to be lengthened and shortened as the adjustment of the crank-pins 40 may require.

This machine is especially intended for sizing fur hats, but it can also be used for sizing and fulling cloth.

Having thus fully described my invention, I 45 claim as new and desire to secure by Letters Patent—

In a fulling-mill, the combination, with the shaft a, that operates the hinged lining-plate, and the cam-roller Q, that operates the beater, 50 of the crank-wheels b d and the connection-rod c, substantially as herein shown and described, whereby the said hinged plate will be operated automatically from the said cam-roller, as set forth.

WILLIAM C. WARING.
